UNITED STATES PATENT OFFICE.

BERL H. WIKE, OF BARRY, ILLINOIS, ASSIGNOR OF ONE-HALF TO EDMUND KELLER,
OF BARRY, ILLINOIS.

FOUNTAIN BLACKING-BRUSH.

1,006,993.

Specification of Letters Patent. Patented Oct. 24, 1911.

Application filed January 14, 1911. Serial No. 602,697.

To all whom it may concern:

Be it known that I, BERL H. WIKE, citizen of the United States, residing at Barry, in the county of Pike and State of Illinois, have invented certain new and useful Improvements in Fountain Blacking-Brushes, of which the following is a specification.

This invention comprehends certain new and useful improvements in fountain or reservoir brushes and relates particularly to brushes of that type that embody a collapsible tube as the main reservoir for the paste or the like, the present invention being designed particularly for use as a shoe blacking brush, although not restricted to that use.

The invention has for its primary object to provide a simple, durable and efficient construction of fountain blacking brush, the parts of which may be cheaply manufactured and readily assembled and which embodies detachable daubing and polishing brushes, whereby the same may be easily cleaned and replaced, as well as improved means for holding a collapsible tube of shoe blacking paste or liquid, preferably the latter, whereby the blacking will be effectually protected when not in use and maintained in proper condition, whereby only the desired amount of blacking will be fed to the dauber, as required, and whereby the blacking applying and polishing operations may be easily and expeditiously performed without any liability of the operator soiling the hands. And the invention also has for its object to provide an improved construction of blacking brush, by the use of which accidental waste will be prevented, as the blacking will not be liable to spill at any time, as often happens when bottles of liquid blacking are used, and to so construct and arrange the parts that the collapsible tubes may be easily applied and replaced when their contents become exhausted.

With these and other objects in view as will more fully appear as the description proceeds, the invention consists in certain constructions, arrangements and combinations of the parts that I shall hereinafter fully describe and claim.

For a full understanding of the invention, reference is to be had to the following description and accompanying drawings, in which—

Figure 1 is a longitudinal sectional view

of a brush constructed in accordance with my invention, parts being shown in elevation; Fig. 2 is a side elevation of the casing designed to protect the collapsible tube; Fig. 3 is an end view of the container head of the device; and, Fig. 4 is a detail view of a key designed to compress the collapsible tube.

Corresponding and like parts are referred to in the following description and indicated in all the views of the drawings by the same reference characters.

Referring to the drawing, the numeral 1 designates the container head of my improved blacking brush, the same being of any desired shape, being octagonal, in the present instance, and being formed near its front edge with a plurality of sockets 2 designed for engagement by a nib which is formed on a spring latch 3 secured to the forward end of a tubular casing 4. This casing is preferably of the same shape as the container head 1 and is adapted to be slipped thereover with an endwise movement as is manifest, the latch 3 snapping into one of the sockets 2 so as to prevent the accidental detachment of the container head from the casing.

The container head 1 is provided in its rear face with an interiorly threaded socket 5 communicating with the rear end of a feed tube 6, the forward end of which leads to a dauber brush 7 preferably detachably connected to the container head as shown. The socket 5 is designed to receive and be engaged by a threaded nipple 8 which is formed on one end of a collapsible tube 9 designed to contain liquid blacking. After the tube 9 has been connected to the container head, the casing 4 is slipped into place on the container head and fastened. The casing 4 is formed with one or more longitudinally extending slots 10, there being two of these slots in the present instance located in diametrical relation to each other, and said slots are designed for the purpose of permitting the insertion of a key 11, one end of which is bifurcated as indicated at 12, whereby it may be slipped over the rear end of the tube 9 and within the casing and cause the contents of the tube to exude therefrom, when the key is twisted or turned. In addition to the slots 10, the casing 4 is preferably formed with a plurality of openings 13 which may be more or

less ornamental in character, as desired, and which may also be used to view the tube 9 within the casing to determine the exact condition thereof. In addition to the 5 dauber 7, the container head 1 carries a polishing brush 14 which is preferably detachable and which in the present embodiment of the invention faces in a direction opposite to that in which the dauber 7 faces, 10 being secured to the forward converging ends of the brace rods 15, the rear ends of said rods being connected to the head 1.

From the foregoing description in connection with the accompanying drawing, 15 the operation of my improved blacking brush will be apparent. In the practical use of the device, a tube 9 is secured to the container head 1 and the protective casing 4 is then slipped into place, being secured to 20 the container head by engagement of the latch 3 in one of the sockets 2. The device is then ready for use and it is obvious that by turning the key 11, the blacking may be caused to flow out of the nipple 8 through 25 the tube 6 so as to moisten the brush 7 by which it may be readily applied to the boot or shoe, after which the polishing brush 14 is used in the usual manner. By using a collapsible tube and a key therefor, it is 30 clear that only the required amount of blacking will be fed to the dauber, that the device may be manipulated without any danger of the hands of the operator becoming soiled, that all accidental waste will be 35 prevented, and that the blacking will be preserved for a comparatively long time and maintained in proper condition, as it is not exposed to the light or liable to become wasted through evaporation. There is no 40 liability of misplacing or losing the brushes, as the device carries its own brush which is detachable and capable of being cleaned or replaced by new ones.

It is, of course, to be understood that in 45 the preferred method of disposing of my improved blacking brushes, a set of collapsible tubes will be sold with one brush,

all of the parts being packed in a box in an evident manner, whereby the user may have at hand a relatively large supply of blacking and not be compelled to at once purchase a new tube after one tube has been used up.

In the preferred method of attaching the polishing brush 14 to the brace rods 15, the 55 latter are connected together by a plate 16 carrying one or two set screws 17. The back of the polishing brush is provided with a threaded boss 18 designed for engagement in a threaded socket 19 formed in the plate 60 16, and after the boss has been screwed into the socket, the set screws 17 are worked outwardly so as to impinge against preferably metallic abutments 20 carried by the back of the brush, as clearly illustrated in Fig. 1. 65

Having thus described the invention, what is claimed as new is:

A brush of the character described, comprising a container head, braces secured to and projecting forwardly from said head, a 70 plate secured to the converging forward ends of said braces, the plate being formed with a threaded socket, a brush back formed with a threaded boss working in said socket, the back being also provided with abutments, 75 set screws working through the plate and adapted to impinge against said abutments, a dauber secured to one of said braces, a feed tube leading from the dauber into the container head, said head being provided in its 80 rear face with a socket into which the rear end of the feed tube opens, a collapsible tube provided with a nipple adapted to be secured in said socket, and a casing designed to be slipped over said tube and arranged 85 for detachable connection to the container head.

In testimony whereof, I affix my signature in presence of two witnesses.

BERL H. WIKE. [L. s.]
